UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

CIRCUIT-BREAKER AND SWITCH.

1,269,156.

Specification of Letters Patent. Patented June 11, 1918.

Application filed April 4, 1916. Serial No. 88,803.

To all whom it may concern:

Be it known that I, GEORGE A. BURNHAM, a citizen of the United States, residing at Saugus, in the county of Essex and State 5 of Massachusetts have invented an Improvement in Circuit-Breakers and Switches, of which the following is a specification.

In certain types of circuit-breakers now on the market, a latch is employed for holding the operating-member with the movable switch-member in closed position, and a tripping-coil is provided for moving said latch to release the operating-member and permit the movable switch-member to move 10 into open position. There is considerable strain exerted upon the latch by the operating-member, due to the weight of the switch-member and its consequent tendency to open, particularly in large circuit-breakers, and, as a result, considerable power is 15 required to move said latch to disengage the operating-member. The tripping-coil is usually made of proportions larger than need be, in order that it may operate to move 20 the latch, upon an overload or other abnormal condition of the circuit, but, in case it should fail and consequently fail to disengage the operating-member, the result would be disastrous.

Furthermore, in the manufacture of circuit-breakers, both the operating-member and the latch are usually pivotally supported more or less loosely to insure the 25 correct engagement of the contacts. On account of this looseness, both elements wabble more or less on their supports, and when in certain relative positions, bind or cramp, and in such event, movement of the latch is restrained.

This invention has for one of its objects 30 certain improvements in the latch-engaging means, and also in the latch-supporting means, which enable the latch to be moved easily by a tripping-coil of normal proportions, and insure a prompt or reliable operation of the circuit-breaker; and has for another object, the provision of latch-engaging means, and also latch-supporting means which admit of a wabbling movement of the 35 latch and of the operating-member, yet avoid binding or cramping action.

My improved latch-engaging means and latch-supporting means, either alone, add materially to the freedom of motion of the 40 latch, but I prefer to employ both means.

Figure 1 is a side elevation of a circuit-breaker embodying this invention.

Fig. 2 is a fragmentary sectional detail, the latch being shown in plan.

Fig. 3 is an enlarged side elevation of the 50 latch and associated latch-engaging element and supporting-means.

Fig. 4 is a fragmentary view, in front elevation, of the operating-member.

Fig. 5 is a vertical sectional detail of the 55 latch-engaging element.

Figs. 6 and 7 are vertical sectional views of an end-portion of the pivot-shaft of the latch and bearings, therefor, in different 60 relative positions.

The circuit-breaker here shown comprises an arm 10, pivoted at 11, and bearing a bridging contact-member 12, adapted to engage contact-members 13, 14; and an auxiliary contact-member 15, adapted to engage 70 contact-members 16, and another contact-member 17 adapted to engage a contact-member 18. A link 19 loosely connects said pivoted arm 10, with an arm 20, of a bell-crank which is pivoted at 21, the other arm 80 22, of which bell crank is arranged to serve as and constitute the operating-member or handle.

When the operating-member or handle 22 is pressed down, the circuit-breaking element is closed, and said element is held 85 closed by a latch 30, engaging said handle, but when the latch is moved to disengage the handle, said circuit-breaking element is permitted to open, hence it is biased to open 90 position.

This structure, however, is intended merely to typify a general form of circuit-breaker, to which my invention is applicable.

The operating-member 22 has a hole 95 through it, see Fig. 4, in which is arranged transversely a rod 25, and on said rod there is loosely mounted a ring 26, see Figs. 3 and 5, having an outer peripheral groove which receives a set of balls 27, which latter are 100 held in place and in spaced apart relation by a separating-ring 28, and an outer ring 29 is loosely arranged on said balls, it having an inner peripheral ball-receiving groove for the balls. The outer periphery of said 105 ring 29 is of circular formation, and is flat and smooth to form a latch-engaging surface. These three components, namely, the ring 29, and the set of balls 27, and the ring 26, are all rotatable freely about a hori- 110

zontal axis and serve as the latch engaging-element. The outer ring 29 is free to oscillate slightly, or to a limited extent, about an axis at right angles to its horizontal axis of 5 rotation, as illustrated in Fig. 5, yet in any angular position, it may occupy, relative to the rod 25, is adapted to freely rotate.

30 represents the latch which is pivoted at 31. Its latch-formed end engages the 10 outer periphery of the ring 29, and when moved either up or down, acts to move the ring rotarilly in a corresponding direction, and the latter being supported on ball bearings, is freely revoluble, so that movement 15 of the latch is not restrained, even when exerting considerable pressure in the ring.

As here shown, the latch-formed end-portion of the latch has two engaging faces 32 and 33, arranged at right angles with relation to each other and adapted to engage 20 tangentially the ring 29, the engaging face 33 being adapted to ride along upon or with the rotatable engaging element, and the engaging face 32, limiting the downward movement 25 of the latch. Said latch-formed end also has an outer curved engaging-face 34, adapted to be engaged by the rotatable latch-engaging element when the handle is moved into latch-engaging position. The pivot 31 30 of the latch is arranged in a housing 40, which is supported by a pivot-shaft 42. Said housing comprises a pair of spaced-apart side plates 41, 41, a top cross bar 45, and a bottom cross bar 46, all integrally 35 formed or joined together. The pivot 31 for the latch is arranged between the side plates near the rear of the housing. The pivot shaft 42 is divided intermediate its length, and the housing is arranged between 40 its component parts and is joined to the side plates 41, 41, in front of the pivot 31 so that the housing projects in rear of the pivot-shaft. The latch 31 has a lug 47 extended downwardly, which engages the bottom cross-bar 46, and movement of the latch 45 is caused by a movement of the housing and pivot-shaft to which it is connected. The cross-bar 45 serves to limit upward movement of the latch.

50 Said cross-bar 46 is arranged in the path of movement of an arm 50, of a bell-crank lever, which is pivoted to the frame, the other arm 52 of said lever bearing the armature 53 of the tripping-coil 54. This armature is normally retracted, but when attracted, upon energization of the tripping-coil, the arm 50 will be moved to strike the cross-bar 46 of the housing, and will move the housing on the axis of the pivot-shaft 42, and said cross-bar will, in turn, by engagement with the lug 47 on the latch, lift said latch on its pivot 31 to disengage the engaging-element on the operating-member.

To limit the oscillating movement of the 65 pivot-shaft 42, there are fixed to said shaft

two dogs 56, and 57, which are extended radially, one of which, as 56, is adapted to engage one edge of a plate 58, secured to the frame, and the other, as 57, is adapted to engage another edge of the plate 58. The 70 dog 56 limits the movement of the shaft in a direction to permit the latch to engage the latch-engaging element, and the dog 57 limits the movement of the shaft in the other direction. The pivot-shaft 42 has self-aligning bearings engaged by its end-journals. This is of particular advantage in case of a multipole circuit-breaker, wherein the pivot-shaft 42 is extended to include all of the breaking elements, and is adapted for 80 oscillation by the trip coil of any of the breaking elements, as in such case, the circuit-breaker is usually shipped knock-down, and adapted to be set up, upon arriving at its destination. 85

Referring to Figs. 6 and 7, the pivot-shafts of the breaking elements have their adjacent end-journals adapted to be connected together, as, for instance, they may have threaded sockets to receive the threaded 90 ends of connecting rods 70, which rods are connected together by a coupling 71.

The end-journals 60 of the pivot-shaft 42 are received in circular holes in inner rings 61, which are formed with peripheral grooves 95 to receive balls 62, which are held in place therein, in spaced-apart relation, by separating rings 63, and outer rings 64, having inner peripheral or receiving grooves are arranged on the balls, and said outer rings 100 have flat outer peripheries adapting them to be set in circular recesses in the supporting frames. The pivot-shaft is thus supported at its ends in ball-bearing supports, and hence are freely rotatable in the ball-bearing elements here shown. Furthermore, the inner rings 61 are adapted to oscillate through short arcs on axes at right angles to the axes of rotation of the pivot-shaft, thus admitting of self-alignment, of the 110 pivot-shafts, as occasion demands.

I claim:

1. A circuit-breaker having a movable switch-member, an operating-member for it, locking-means for said operating-member, 115 one of the component elements of which is adapted for angular movements and for rotation in any angular position it may occupy, and a tripping-coil controlling said locking-means.

2. A circuit-breaker having a movable switch-member, an operating-member for it, locking-means for said operating-member, one of the component elements of which is adapted for rotation and is equipped with a 125 ball bearing, one member of which is adapted for angular rotation with respect to a stationary member, and a tripping-coil controlling said locking-means.

3. A circuit-breaker having a movable 130

switch-member, an operating-member for it, a latch, a trip-coil for the latch, a support borne by the operating-member and a latch-engaging element arranged on said support 5 and adapted for angular movement with respect to its support and also for rotation in any position it may occupy.

4. A circuit-breaker having a movable switch-member, an operating-member for it, 10 a latch, a trip-coil for the latch, and a rotatable latch-engaging element borne by the operating-member equipped with a ball bearing, one member of which is adapted for angular rotation with respect to a stationary member.

5. A circuit-breaker having a movable switch-member, an operating-member for it, a latch, a trip-coil for the latch, and a latch-engaging element borne by the operating- 20 member, comprising a ring and a support on which said ring is free to move rotarily, and also to oscillate about an axis at right angles to its support.

6. A circuit-breaker having a movable switch-member, an operating-member for it, 25 a latch, a trip-coil for the latch, and a latch-engaging element borne by the operating-member comprising a rod, an inner ring arranged thereon having a peripheral ball-receiving groove, a set of balls arranged in

said groove, a separating-ring for the balls, and an outer ring arranged on the balls, and free to rotate about the rod as an axis, and also to move angularly with respect thereto.

35

7. In combination with a circuit breaker having a movable member and an operating member therefor having latch engaging means, of a latch, a pivot shaft, a housing for the latch arranged on said shaft intermediate the length thereof, a pivotal support for said latch arranged in the housing in the rear of the axis of the pivot shaft, and a tripping coil for the latch.

40

8. In a circuit-breaker having a movable switch-member, an operating-member for it, a latch, a latch-engaging element on the operating-member, a support for the latch comprising a pivot-shaft having end-supports adapted for angular movements, and 50 for free rotation in any angular position it may occupy.

45

In testimony whereof, I have signed my name to this specification, in the presence of two subscribing witnesses.
